SWITCH KNOB

Melvin H. Boldt, Chicago, Ill., assignor to Moffats, Limited, Weston, Ontario, Canada, a corporation of the Province of Ontario

Filed Mar. 6, 1963, Ser. No. 73,836

Claims priority, application Canada Dec. 29, 1962

Term of patent 14 years

(Cl. D26—13)

FIG. 1

FIG. 2

FIG. 3

FIGURE 1 is a top plan view of a switch knob showing my new design;

FIGURE 2 is a front elevational view of the switch knob of FIGURE 1; and

FIGURE 3 is a side elevational view of the switch knob.

The essential feature of my design resides in the handle member which is tapered and shaped as shown.

I claim:

The ornamental design for a switch knob, as shown and described.
